UNITED STATES PATENT OFFICE.

HERMANN E. SCHILD, OF PITTSBURGH, PENNSYLVANIA.

REVERSING-VALVE.

1,275,609.

Specification of Letters Patent. Patented Aug. 13, 1918.

Application filed March 15, 1918. Serial No. 222,779.

To all whom it may concern:

Be it known that I, HERMANN E. SCHILD, a resident of Pittsburgh, in the county of Allegheny and State of Pennsylvania, have invented a new and useful Improvement in Reversing-Valves, of which the following is a specification.

This invention relates to reversing valves for regenerating and similar furnaces, such as Siemens open hearth furnaces, and similar types of refining and heating furnaces. The object of the invention is to provide a valve for reversing either the air or gas of such furnaces, which is of simple construction, easy to operate, and which when used for reversing the gas prevents wasting the gas and avoids danger of explosions, and to provide a valve which is especially adapted for gas and air ports opening from below so as to avoid overhead conduits.

As is well known, regenerating furnaces are provided with four regenerators or heating chambers for the air and gas, two for the air and two for the gas. Each of these chambers is filled with fire brick or other refractory material known as "checker work" which, upon becoming heated, serves as a means for heating the air or gas passing through the same and before entering the furnace chamber. The air and gas are separately conducted, each through a previously heated regenerator chamber, where they become heated and thence pass to the furnace chamber, and the waste products of combustion pass to the stack through the two remaining regenerator chambers and heat the checker work in the latter, thereby themselves becoming cooled. The first set of regenerator chambers cool off and after a certain time it is necessary to reverse the course of the air and gas, so that the same will then enter through the newly heated regenerator chambers, and thence to the furnace chamber while the waste products of combustion pass out through the regenerators first used, thus reheating the same, and so on alternately.

Various forms of valves have heretofore been provided and suggested for reversing the air and gas, such as butterfly valves and dome-shaped valves mounted either to reciprocate or oscillate. All prior forms of valves have, however, been somewhat com-

plicated and difficult to repair or inspect, and most of them have also been so constructed that they are not adapted to ports opening from below and also so that when reversing there was more or less wastage of gas.

The object of my invention is to provide a reversing valve of simple construction and which is particularly adapted for flues opening from below. The invention comprises a valve mechanism constructed and operating as hereinafter described and claimed.

In the accompanying drawings:

Figure 1 is a vertical longitudinal section of the improved valve adapted for reversing the gas to a regenerating furnace; Fig. 2 is a plan view of the valve seats and showing diagrammatically the checker chambers and connecting flues; and Fig. 3 is a plan view of the valve and its operating mechanism.

In the drawings, the reference numerals 1, 1^a, indicate diagrammatically the checker chambers for the gas and 2 and 2^a the checker chambers for the air. The chambers 1, 1^a are connected by passages 3 and 3^a to gas ports 4 and 4^a in the valve seats 5 and 5^a, while the air chambers 2 and 2^a are connected by passages 6 and 6^a to ports 7 and 7^a in a valve seat 8. In the valve seats 5 and 5^a are a pair of gas ports 9 and 9^a connected respectively to the gas mains 10 and 10^a, and also a pair of ports 11 and 11^a connected by passages 12 and 12^a to the stack, not shown. The valve seat 8 is likewise provided with a port 13 connected by passage 14 to the stack. All of the valve seats named are flat and horizontal and the ports enter through the same from below.

The gas reversing valve comprises a pair of members formed with flat bottom faces fitting and sliding on the seats 5 and 5^a, and which members are in the form of water pans 15, 15^a which are of sufficient length to cover all of the three ports in the valve seats in all operative positions of the valve. Each of the water pans carries a dome-shaped valve member 16, 16^a, preferably lined with refractory material and with the edges thereof dipping below the surface of the water in the pans 15, 15^a and which dome-shaped members are provided with chambers or passages 17, 17^a for direct-

ing the gas and products of combustion in the manner hereinafter described.

The valve described has a simple rectilinear reciprocating movement on the valve 5 seats 5 and 5^a. In one of the positions (shown in Fig. 1) one of the dome-shaped members 16 is in position to connect gas port 9 with checker port 4, thus directing the gas into checker chamber 1, with the 10 left hand end of the water pan 15 covering the stack port 11, while the other dome-shaped member 16^a connects the checker port 4^a with the stack port 11^a, with the left hand extension of the water pan 15^a 15 covering the gas port 9^a. Consequently the gas now enters through the checker chamber 1 to be heated therein, and thence goes to the furnace chamber, while the products of combustion pass through checker chamber 1^a and through the valve member 16^a 20 and thence to the stack. To reverse the gas the valve is merely moved toward the left, so that the dome-shaped member 16 then connects checker port 4 with stack port 11, 25 while the right hand extension of the pan 15^a covers the stack port 11^a.

Any suitable mechanism may be used for reversing the positions of the two valve members in unison. As shown the two pans 30 15 and 15^a are connected by a bar 20 which is toothed so as to form a rack, which is engaged by a pinion 21 on a shaft 22 driven from any suitable source, such as by an electric motor 23. Any other motor, however, 35 may be used, or, if desired, a double acting hydraulic cylinder may be used for reciprocating the valve.

An exactly similar valve mechanism may be used for reversing the air from either 40 port 7 or 7^a to the checker chambers and to the stack, except such valve need have only a single dome-shaped member and the water pan need not be extended so as to cover the third port.

45 The valve mechanism described is very simple and requires a minimum amount of power for reversing. It is admirably adapted to ports opening from below. The valve seats are perfectly flat and the sliding valve members thereon have corresponding flat 50 under surfaces so that there is little danger of leakage of the gas between the valve seat and the valve, and the water cooling of the valve prevents warping and burning out of 55 the valve itself. All of the parts are exposed so that they can readily be inspected and also so that they can be readily gotten at for repair, when necessary.

What I claim is:—

60 1. In a reversing valve mechanism, the combination of a horizontal valve seat provided with three ports opening from below, a sliding valve coöperating with said seat and comprising a dome arranged to connect

two of said ports in each position, a water 65 pan carrying said dome, and mechanism for reciprocating said valve.

2. In reversing valve mechanism, the combination of a horizontal valve seat provided with three ports opening from underneath, 70 a sliding valve comprising a water pan mounted to reciprocate on said seat and carrying a dome arranged to connect two of said ports in each position of the valve, said water pan projecting in both directions from 75 said dome, whereby said projecting ends cover the third port in either position of the valve, and mechanism for reciprocating said valve.

3. In reversing valve mechanism, the combination of two horizontal valve seats each provided with a gas, a regenerator, and a stack port all opening from underneath, a member reciprocally mounted on each of 80 said seats, and including a dome-shaped 85 member, and connections between said reciprocating members, all arranged so that in one position of the valve one of said dome-shaped members connects a gas port with a regenerator port and closes the stack port, 90 and the other thereof connects a regenerator port with the stack port and closes the gas port, and mechanism for reciprocating said members.

4. In reversing valve mechanism, the combination of a pair of horizontal valve seats each provided with a gas, a regenerator, and a stack port opening from underneath, a plate mounted to reciprocate on each of 95 said valve seats and each carrying a dome-shaped member each of which serves to connect two of the ports of the valve seat, said plates being of such length as to cover the third port in each position of the valve, connections between said plates for reciprocating 100 them in unison, and mechanism for reciprocating said valve.

5. In reversing valve mechanism, the combination of two horizontal valve seats each provided with a gas, a regenerator, and a 110 stack port, all opening from underneath, a water pan mounted to reciprocate on each of said valve seats and of a length sufficient to cover all three of said ports in all 115 positions of the valve, a dome-shaped member carried by each of said water pans and arranged in one position of the valve to connect the central port and one end port of each seat, and in the opposite position to connect the central port and the other end 120 port of each seat, and connections and mechanism for reciprocating said pans simultaneously.

6. In reversing valve mechanism, the combination of two horizontal valve seats each 125 provided with a gas, a regenerator, and a stack port, all opening from underneath, a plate mounted to reciprocate on each of said

seats and of a length sufficient to cover all three ports in all operative positions, connections between said plates whereby they move in unison, reciprocating mechanism operatively connected to said plates, and members carried by each plate and forming a conduit arranged in one position to connect the central port with one of the end ports

of each seat and in its opposite position to connect the central port with the other end 10 port of each seat.

In testimony whereof I have hereunto set my hand.

HERMANN E. SCHILD.
